UNITED STATES PATENT OFFICE.

CARROL L. ETHERIDGE, OF JOPLIN, MISSOURI.

POST-WINDER FOR WIRE FENCES.

SPECIFICATION forming part of Letters Patent No. 625,662, dated May 23, 1899.

Application filed January 5, 1899. Serial No. 701,299. (No model.)

To all whom it may concern:

Be it known that I, CARROL L. ETHERIDGE, a citizen of the United States, residing at Joplin, in the county of Jasper and State of Missouri, have invented a new and useful Improvement in Post-Winders for Wire Fences, of which the following is a specification.

For maintaining the line-wires of a wire fence under proper tension I have devised an improved winding-pin attachment for the posts of the fence for winding the line-wires as they may need to be tightened; and my said improvement will be specifically stated in the claims concluding this specification and illustrated in the drawings, in which—

Figure 1 shows in side view a corner-post with the ends of the line-wires secured thereto by my improved winding-pins. Fig. 2 is a horizontal section of the post, showing the winding-pin fastened thereto by staples, collar, and ratchet. Fig. 3 shows the same in side or front view, and Fig. 4 shows the winding-pin with its post engaging collar and ratchet.

The line-wires 1 are passed through holes in the post, and the ends of the wires are secured to and wound upon pins 2, preferably by passing the end of the wire through a transverse hole in the pin, so that by turning the pin the wire will be wound thereon to tighten it throughout the line of the fence. The pin is cylindrical and is secured crosswise to the side of the post by staples 3 and is long enough to project at each end beyond the post. Meditately of its length it has a transverse hole 4 to receive the winding end of the line-wire. A ratchet 5 is formed on the end of the pin, the teeth of which are square like cogs and are engaged by a pawl 6, pivoted to the post to hold the pin when the wire is wound on it. The end 7 of the pin is of square form to receive a winding-key.

It will be noticed that the pin is secured directly against the post by the staples, so that the pins in winding the wires turn against the post. This allows the pins to be locked directly to the post to prevent them from working endwise in the staples.

In stapling the pin to the post the ratchet is brought against that side of the post to

which the pawl is pivoted, and to maintain the engagement of the pawl with the ratchet-teeth it is necessary that the pin be secured from slipping endwise in the staples, as it is liable to do by winding the wire on the pin, 55 and in such event the pawl would be liable to leave the ratchet-teeth or to have an uncertain hold on them. As a means of holding the pawl and ratchet in their true relation I provide the pin with a circumferential annular projection 8, adapted to engage the side of the post opposite to that engaged by the ratchet, and so lock the pin thereto to prevent it from moving endwise in its fastening-staples. This circumferential projection is 65 formed by a loose collar 8, fitted on that end of the pin opposite the ratchet end and against the side of the post and fastened in place on the pin by a key 9, passed through a hole in the pin, as in Fig. 2. The ratchet and the 70 collar fitted on the opposite ends of the pin and against the opposite side of the post serve to hold the ratchet and pawl in safe engagement. This means of preventing the winding-pin from endwise movement avoids the 75 expense of housing or mounting the plates on the posts which have hitherto been used with winding-pins.

The collar may be fitted loosely on the pin, or it may be formed with it. In both cases the 80 pin is engaged with the post, so that the ratchets will always be kept in proper relation to the pawl and the pins always kept in the fastening-staples. The square form of ratchet-teeth allows the winding-pin to be 85 used either right or left handed and on dividing-fences. When the circumferential projection is formed by the loose collar the pin has a hole to allow the collar to be keyed against the post with the ratchet fitting against 90 the other side of the post without regard to its thickness. By stapling the pins they are ready to receive the wires when the post is set.

I claim as my improvement—

1. A post winding-pin for wire fence having a ratchet at one end and an annular projection at or near its other end for engaging the opposite sides of the post whereby the pin is prevented from moving endwise on the 100

post combined with the line-wires, and post, the fastening-staples and the pawl.

2. In a post-winder for wire fences and in combination with the line-wires and the post,
5 of the winding-pin having the loose collar on one end, a ratchet-wheel on its other end, a pawl engaging the latter and a key for hold-

ing the collar on the pin, the ratchet and the collar engaging the opposite sides of the post, and the fastening-staples for the pin.

CARROL L. ETHERIDGE.
